[57] ABSTRACT

A shed for fitment over the discharge side of a coke oven battery has a roof the ridge of which contains a dust and gas extraction system and the roof slopes downwardly from the wall thereof opposite the battery to the wall thereof adjacent the battery. The dust and gas extraction system is connected to a scrubber wherein impurities are removed from the air flow using water from the supply made available for quenching purposes.

SHED FOR THE DISCHARGE SIDE OF A COKE OVEN BATTERY

This invention relates to a shed for the discharge side of a coke oven battery, the coke ovens forming at least part of one of the longitudinal walls of the shed and the shed having an inclined roof. The opposite longitudinal wall of the shed includes supporting pillars and the shed contains a dust and gas extraction system mounted in the roof thereof.

A shed of the kind referred to above surrounds the tracks on which the coke trolleys are arranged to run and sits over the oven doors. The use of such sheds enables one to reduce the obnoxious emissions normally associated with coke oven batteries because the dust and gas extraction systems which are at the discharge side of the battery are of high efficiency and the sheds can be kept substantially closed.

In a known shed of the kind referred to above, the roof slopes downwardly from the side adjacent the coke oven battery towards the opposite side thereof and consequently the ridge of the roof is located immediately to the rear of the battery. Because the height of the wall opposite the battery must be at least a predetermined amount, a relatively large proportion of the longitudinal wall of the shed adjacent the battery is not formed by the walls of the ovens. This means that the ovens have to support a substantial weight constituted by the weight of this portion of the wall of the shed.

The weight which has to be supported is not, however, merely the weight of the shed structure but also the weight of the dust and gas extraction system. Such system has to be arranged at the ridge of the roof since the airborne dust and gases will tend to gather at the highest part of the shed because of the internal air flow conditions. The known shed design referred to above thus has the disadvantage that the hot gases and airborne dust are forced towards the walls of the ovens and this means, in particular in summer, that the temperature adjacent the top of the battery can be excessive.

In the structure of the known shed referred to above vertical tie bars are employed together with cantilever beams which project at both sides beyond the supporting pillars. This means that a relatively large space outside the shed is occupied by the shed structure and that the amount of constructional material required is considerable.

It has previously been proposed to employ a perforated gas extraction pipe which is arranged in the ridge of a shed roof, which roof is inclined downwardly from the oven battery towards the opposite longitudinal wall of the shed. Such proposal was, however, included in a shed which was heavy and expensive to produce and it is an object of the invention to provide a shed which does not cause excessive loading of the structure of the coke oven battery, is less expensive to produce than known sheds for this purpose and which further is so designed that the internal air flow conditions are such as to avoid excessive temperature increases adjacent the top of the battery.

According to the invention there is provided a shed having the features set out above and for fitment over the discharge side of a coke oven battery wherein the roof is inclined upwardly from the side adjacent the battery towards the opposite wall thereof and wherein the ridge of the roof which contains the dust and gas ex-

traction system is located at the junction between the roof and said opposite wall of the shed.

The flow conditions within the shed will thus facilitate removal of the emissions produced during discharge of coke from the ovens and also the removal of fumes which escape around the oven doors if these are not properly sealed. By arrangement of the dust and gas extraction system adjacent the wall remote from the oven battery, the gas and dust is drawn away from the ovens and this means that the electrical equipment which is normally arranged above the coke receiving trolley on the discharge side of the battery is less affected by corrosion. Moreover, because the weight of the extraction system is immediately adjacent the supporting pillars of said opposite wall of the shed, the roof loading is reduced, the roof being of cantilever design and further the load transmitted to the roof of the oven battery is also reduced.

Tie bars for supporting the roof and the wall of the shed spaced from the battery are preferably provided which are inclined downwardly from the roof ridge, the arrangement providing considerable economies in the supporting pillars of said wall. It also provides for a reduction in the total weight of the shed structure.

In order to regulate the supply of air to the interior of the shed, the wall of the shed spaced from the battery can be provided with adjustable flaps. Openings in the side walls of the shed through which coke wagons pass into and out of the shed are preferably automatically opened and closed. This arrangement enables one to control air flow conditions within the shed and permits dissipation of the hot gases and vapours to the wall of the shed away from the battery.

The invention enables one to reduce the height of those parts of the shed other than the longitudinal wall spaced from the shed and the roof and that part of the shed wall adjacent the battery not formed by the walls of the ovens may be supported through roller bearings on the roof of the coke oven battery. These roller bearings may be spring-loaded and it has been found that this form of resilient support does not adversely affect the structure of the coke oven battery.

In an alternative arrangement, the roof of the shed is designed so that it is solely supported by the wall of the shed remote from the battery. The shed can be a simple structure with a sheet metal lining. Alternatively it can be of reinforced structure with a lightweight concrete lining.

The dust and gas-laden air which is drawn from the shed must, of course, be cleaned before it is released into the atmosphere. Centrifugal separators and filters containing fabric materials are known but these have not permitted removal of the smoke and tar fractions which the air has contained. Attempts have therefore been made to remove these materials by spraying water on the air before the air passes through a series of fan blowers.

A large scale trial in respect of the above proved successful and it was found that deposits tended to form on the rotating parts of the fans or blowers causing these to become unbalanced. Another attempt to precipitate the emitted dust and gases in a cyclone stalled after the fan or blower produced a number of problems which were concerned primarily with high solids contents of the residues, the solids causing blockage of the flow lines. Thus, in accordance with

further feature of the invention, improved means are provided for removing the dust, smoke and condensable constituents from the air drawn out of the shed. A part of the water employed to quench the coke is diverted and is used to wash the dust-and gas-laden air extracted from the shed, the air being washed before entry thereof into the blowers.

By use of a portion of the water employed to quench the coke as a washing agent for the dust-and gas-laden air, the washing water containing the impurities can be cleaned in existing filter plants and can therefore be circulated continuously. The amount of water required for quenching purposes is considerably greater than that required to remove the impurities from the air flow and thus no additional pumps need be installed and the quenching water circuit is readily extendable.

The residues removed from the scrubbing water will consist mainly of coke particles which can be delivered into the coke quenching water settling tank since these are identical with the coke slag. Unexpectedly, it has been found that, by using a scrubbing process as set out above, tar vapour impurities are readily removed because the tar is absorbed by the coke particles and is removed together with the coke particles. The problems previously encountered concerning the formation of deposits upon the rotating parts of the blowers are thus avoided. During the scrubbing operation the dust-and gas-laden air drawn from the shed can be caused to flow in counter-flow relation with the scrubbing water, the air being allowed to flow upwardly and the water being sprayed downward through it.

In an alternative arrangement, the dust-and gas-laden air is caused to flow in the same direction as that portion of the coke quenching water which is diverted for scrubbing purposes, this water being atomised so as to saturate the air-stream at the commencement of scrubbing whereas, at the end of the scrubbing operation, the water is introduced as larger drops to precipitate coarse impurities in the air.

It is preferred that the scrubbing process described above be carried out in a spray scrubber which does not include baffle plates. Relatively high air velocities and high spray densities can be obtained and this ensures not only effective dust removal but also effective removal of the tar vapour in the air-stream. Blockages in the scrubbing system are avoided and the low pressure drop in such a scrubber has a favourable effect on the power consumption of the fans or blowers of the dust and gas extraction system.

The treatment plant may include a vertical scrubber situated in the extraction line before the fans or blowers of the dust and gas extraction system, the vertical scrubber having a connection at its upper end for the introduction of the dust-and gas-laden air with a series of nozzles at different levels within the scrubber, the nozzles at the higher level or levels being so designed that the water issuing therefrom is atomised whereas the nozzles at the lower level or levels are such as to form droplets of the coke quenching water, the scrubber being provided at its lower end with a discharge outlet for the passage of the scrubbed air to a cyclone the lower end of which is provided with means for carrying out a rinsing operation using the scrubbing water collected in the scrubber.

The invention will now be described by way of example with reference to the accompanying drawings wherein:

FIG. 1 is a diagrammatic cross-sectional view of a coke oven battery and a shed designed to cover the discharge side of the battery and,

FIG. 2 is a schematic view of a coke oven battery, shed and extraction equipment.

The battery of coke ovens 1 has a top 2 over which the usual charging truck 3 can be traversed longitudinally of the battery. The usual clearing truck is movable along the front 4 of the battery although this has not been shown. At the opposite side 5, normally referred to as the discharge side, a coke delivery trolley 7 runs on rails 6, the trolley being operated through trolley wires 8. The discharge side 5 of the battery of ovens is covered by a shed structure 9.

One of the longitudinal walls of the shed structure is partially formed by those walls 10 of the ovens which face towards the discharge side. A small part of this longitudinal wall of the shed is marked 11 and consists of dependant rods 12 to which a lining 13 is attached, the lining being made up of sheet metal or light concrete sections. The shed roof 14 is inclined. Its beams rest upon vertical pillars 15 and obliquely extending tie bars 16 are provided which terminate at foundations 17. Stiffeners 18 link the tie bars 16 and the pillars 15.

The roof ridge 19, i.e. the highest point 19 of the roof which slopes downwardly towards the coke ovens 1, is at the junction between the roof and that longitudinal wall 20 of the shed which is disposed opposite the oven walls. The longitudinal wall 20 of the shed, like the roof 14, consists of sheet metal liners or lightweight concrete liners supported on the pillars 15 and the roof beams.

At the ridge 19, there is a dust and gas extraction system including a pipe 21. The fans and the dust-separation equipment associated with this pipe 21 have not been shown. The tie bars 16 terminate at the ridge 19 of the shed.

To regulate the air supply to the shed, that longitudinal wall 20 of the shed which is located opposite the ovens walls 10 is provided adjacent a coke ramp 26 with an adjustable flap. Also, the transit openings for the coke delivery trolleys 7 are equipped with automatically opening and closing doors. Other flaps 23 regulate openings 24 which are provided adjacent the ridge 19 of the shed, i.e. near the top of the longitudinal wall 20. The air supply to the shed is controlled by means of the flaps 22 and 23, which can be connected together through a linkage 28. A catwalk 25 is suspended from the pillars 15 and enables operators to observe not only the flaps 22 and 23 but also associated openings of lighting systems arranged in the top part of the shed, as well as the equipment housed in the shed, this including coke discharge wagons 27.

The coke oven battery has been marked 201 in FIG. 2, its discharge side 203 being covered by a shed structure 204. The shed has vertical pillars 205 set in foundations 206, and a roof 207 inclined downwardly towards the coke ovens 201. When the coke oven doors are opened, a convection flow is obtained in a direction towards the higher parts of the shed structure 204 and a dust and gas extraction system 209 is located substantially at the ridge of the shed 204.

Of this device, in the drawing, only a collecting line 210 has been shown and this is provided at spaced intervals with inlet connections 211. During discharge of the coke from an oven into the coke wagons 212, there is a considerable emission of dust and obnoxious gases.

This emission passes into the collection space at the top of the shed and is drawn upwards into the line 210 and fed to a scrubber 213. The scrubber has a connection 214 at its upper end for the line 210 and, within the scrubber, a plurality of nozzles 215 and 216 are arranged in groups at two different levels.

Both groups of nozzles receive scrubbing water from a line 217, which water is drawn from a quenching water vessel 218. The quenching water vessel 218 forms part of a coke-quenching tower 219 in which the quenching water is sprayed down on to wagons 212 holding the glowing coke. The spent quenching water collects in a settling tank 220 from which it is extracted by means of a pump 221 and recycled through a line 222 to the vessel 218.

A sump 223 is used to collect the solids which are drawn off by means of a pump 224 through a line 225 into a coke breeze bunker 226. As can be seen, the quenching water circuit is a closed circuit, and thus it is only the losses occurring during the quenching operation which have to be made good by the addition of further water.

The top group of nozzles 215 atomise the water delivered therefrom so that the air introduced into the scrubber 213 at 214 is saturated. The group of nozzles 216 arranged at the lower level, produce larger droplets at a relatively high density. Thus, smoke particles, tar vapour and larger dust particles are precipitated. The descending water droplets collect in a sump 230 at the bottom of the scrubber 213. The scrubbed air is drawn off at 231 and fed into a cyclone 232 which is connected to one or more blowers 233 which deliver the air to the atmosphere at 234. The scrubbing water is drawn from the sump 230 and fed through a line 235 to the bottom part 236 of the cyclone 232, and thence together with the residues from the cyclone through a line 237 into the settling tank 220. Here, the solids, mainly coke particles, pass into the sump 223 by sedimentation. The dust-and gas-laden air passes downwards through the scrubber 213. As a result, high gas velocities and a multi-stage water jet system, can be used.

We claim:

1. A shed structure for covering the discharge side of a coke oven battery, comprising an upright wall spaced laterally from the coke oven battery and forming with the side of the oven battery an enclosure, a roof inclining upwardly and outwardly from the top of the oven battery to said upright wall, a dust and gas extraction system located within the shed structure at the ridge or junction between said roof and said upright wall, said upright wall including vertical reinforcing pillars extending throughout the height of the wall and upon

which said roof rests, and tie bars supporting said roof and wall inclining downwardly and away from said ridge.

2. A shed structure as claimed in claim 1, comprising a relatively short wall portion of the shed constituting substantially an upward continuation of the adjacent oven battery and to which the lower end of the incline roof is fixed.

3. A shed structure as claimed in claim 1, comprising flaps for regulating the air supply to the shed, said flap including flaps at the lower portions of said upright wall and flaps at the upper portions of said wall, and linkages connecting said upper and lower flaps for actuating same.

4. A shed according to claim 2, wherein the roof and that part of the longitudinal wall of the shed not constituted by the walls of the ovens on that side of the shed adjacent the ovens is supported by roller bearings upon the roof of the coke oven battery.

5. A shed according to claim 4, wherein the roller bearings are spring-loaded.

6. A method of operating a shed for a coke oven battery which includes a dust and gas extraction system located adjacent the ridge of the roof of the shed, said method being characterised in that the dust-and gas-laden air extracted from the shed is scrubbed with water before passing to blowers forming part of said extraction system, this water being part of the supply used for coke-quenching purposes.

7. A method according to claim 6, wherein the water used to scrub the dust-and gas-laden air is thereafter fed to a settling tank of the quenching system.

8. A method according to claim 6, wherein the dust-and gas-laden air flows in the same direction as the water used for scrubbing purposes and wherein the scrubbing water is introduced as a first portion which is atomised to saturate the air and a second portion which is in the form of droplets and serves to precipitate solid impurities.

9. Apparatus for use in the removal of impurities from the dust and gas extraction system of a shed for a coke oven battery, said apparatus including a vertical scrubber which has a connection at its upper end for the introduction of dust-and gas-laden air and is provided with nozzles at a first level through which atomised water is introduced with further nozzles at a lower level which form droplets of water, the scrubber being provided with an outlet at its lower end and the outlet being connected to a cyclone which includes means for carrying out a rinsing operation on the scrubbed air using the scrubbing water collected in the scrubber.
